Attorney, Agent, or Firm—Albert M. Herzog; Edward C. Walsh

[57] CLAIM

The ornamental design for an etagere, substantially as shown and described.

DESCRIPTION

FIG. 1 is a front perspective view of an etagere showing my design;

FIG. 2 is a side view of the design of FIG. 1;
FIG. 3 is a top view of the design of FIGS. 1 and 2;
FIG. 4 is a sectional view of the design taken along line 4—4 of FIG. 1;

FIG. 5 is a sectional view of the etagere taken along lines 5—5 of FIG. 1; and

FIG. 6 is a front perspective view thereof.
